ORNAMENT AND FRAME THEREFOR

Leo K. Stupell, New York, N. Y.

Application October 5, 1935, Serial No. 43,704

6 Claims. (Cl. 40—140)

My present invention relates to improvements in ornamental jewelry, and has particular reference to ornaments such as initial letters and the like, and frames therefor.

5 My present invention is an improvement on the construction disclosed in U. S. Patent No. 1,921,437, granted August 8, 1933, and is designed to facilitate and to improve the mounting of initials or other ornaments in ornamental receiving openings provided in ornamental frames and the like.

It is the principal object of my invention to devise a construction for facilitating the hand insertion of ornaments into suitable openings of 15 frames, whereby the ornaments may be selectively positioned in said openings and securely locked therein against accidental removal.

It is a further object of my invention to provide a construction whereby an ornament, when 20 locked into a frame, is securely held against lateral displacement, whereby the ornaments are rigidly secured in fixed relation.

It is an additional object of my invention to utilize a selective spacing arrangement to guide 25 a purchaser or a clerk in properly spacing the ornaments within a frame or the like.

With the above and other objects and advantageous features in view, my invention consists of a novel arrangement of parts more fully disclosed in the detailed description following, in conjunction with the accompanying drawing, and more specifically defined in the claims appended thereto.

In the drawing: 35

Fig. 1 discloses an assembly of an ornamental frame having selected initials mounted therein;

Fig. 2 is a rear view of the frame;

Fig. 3 is a plan view of a novel initial ornament;

Fig. 4 is a side view thereof;

Fig. 5 is a section on the line 5—5 of Fig. 2, showing the locking arrangement between the frame and the initial;

Fig. 6 is a section on the line 6—6 of Fig. 2;

Fig. 7 is an enlarged sectional detail showing the interlocking engagement of the initial and the frame;

Fig. 8 is an enlarged sectional detail similar to Fig. 7, but showing a modified construction of initial and of the cooperating frame;

Fig. 9 is a perspective detail of the initial of Fig. 8; and

Fig. 10 is a perspective detail of the frame of Fig. 8.

Referring to the drawing, the novel ornament includes a plurality of ornaments, such as initial letters 10, which are adapted to be selectively locked into a frame 11, as by contact with the walls of an opening 12 formed therein. The 5 frame is formed so as to provide two resilient sides 13, 14, and the two sides are each grooved as indicated in Figs. 2 and 6 to provide a recessed section 15 having an inwardly extending edge 16 which is bevelled at the end thereof as indicated at 17, spaced recesses 18 of any suitable size and distance apart being also provided at suitable intervals along the edge 16, the recesses being preferably square as shown.

The initial letters 10, see Figs. 3 and 4, are 15 grooved at each end as indicated at 19, the grooves being shaped to correspond with the bevelled upper and lower edges 17 of the opening 12. The base of each initial letter is extended at each end to provide lugs 20, which as 20 illustrated at Fig. 3, are spaced apart and are of rectangular form so as to snugly fit into the recesses 18 provided therefor on the edges 16.

When placing the initials in the frame, the lower lugs 20 are inserted at the back of the 25 frame so as to contact the lower edge 16, with the lower bevel and groove in contact, and the initial is then moved forwardly until the upper groove 19 snaps over the upper bevelled edge 17, the sides 13 and 14 of the frame yielding sufficiently to permit the snapping engagement and to prevent movement of the top of the initial through the frame; both the upper and lower lugs 20 are received in the contiguous spacing recesses 18, whereby the initials cannot shift laterally. Snapping of the initials in the frame is aided by bevelling the edges of the initials, as indicated at 21. Selection of the spaces to use depends on the size of the initial or other ornament, and on the number of initials to be snapped into the frame, as the lugs 20 and the recesses 18 form selective guide and positioning means for setting the initials in proper desired relation in the opening, and therefore in the frame.

Instead of utilizing edges 16 on the frame, a 45 similar result is obtained by forming the frame as indicated at 22, Fig. 8, with upper and lower flanges 23, and a bevelled base 24, the flanges having spaced guide and positioning recesses 25, and the initial 26 being formed with correspondingly grooved upper and lower edges 27 and guide and positioning projections 28 on the face for seating into the recesses 25. With this construction the initial is set with its lower edge against the lower flange 23 and its projections 28 en- 50 55

gaging the recesses 25, and the upper edge is then snapped into the frame, the frame giving sufficiently to permit the snapping action.

The above described construction utilizes the resilience of the frame edges to hold the initial in place after it has been inserted in the frame. It is possible to utilize a relatively rigid frame and relatively resilient ornaments, whereby the initial letters or other ornaments may be slightly flexed so as to lockingly engage the opposite edges of the frame opening, the initials then lengthening due to their elasticity and thus locking the initials in place on the edges. A preferred arrangement for this purpose is to have the initial letters grooved on their upper and lower edges and the upper and lower edges of the frame opening bevelled; any other desired arrangement for accomplishing the snap-in relation may be utilized. The essential feature of the modified form resides in the slight bending of the initial to permit movement of the initial edges into locking relation with the edges of the frame opening, the locking relation being completed by straightening movement of the initials.

The frame and initial construction described may be used in brooches, pins, for ornamenting hand bags, garments, millinery, and for other decorative purposes; instead of a frame opening a depressed recess may be used, as in the covers of vanities, powder cases, cigarette cases, and the like; the edges of the frame opening are preferably integral, but may be separate and secured to the frame in any desired manner.

While I have described specific constructional embodiments of my invention, it is obvious that desired changes in the materials used for the frame and the initials, in their decoration and ornamentation, in the type, shape, and arrangement of the ornaments, in the relative mounting of the ornaments in the frames, and in the size of the frames and the openings therein, may be made to suit the requirements for different designs.

I claim:

1. In combination, an ornament holder member comprising a frame having an opening, and an ornament member adapted to seat in said opening, said members being made of metal, the edge parts of said frame opening and of the ornament member having complementary grooves and projections, one of said members being of elastic material whereby said ornament member may be snapped into said frame with said complementary parts engaging to lock said ornament member in said frame, and means on said members for guiding the engaging movement of said parts, said members having means for preventing movement of the ornament member parts past the holder member parts when engaged for snapping together.

2. In combination, an ornament holder member comprising a frame having an opening, and an ornament member adapted to seat in said opening, said members being made of metal, the edge parts of said frame opening and of the ornament member having complementary grooves and projections, one of said members

being of elastic material whereby said ornament member may be snapped into said frame with said complementary parts engaging to lock said ornament member in said frame, one of said members having a lug and the other of said members having a recess for receiving said lug.

3. In combination, an ornament holder member comprising a frame having an opening, and an ornament member adapted to seat in said opening, said members being made of metal, the edge parts of said frame opening and of the ornament member having complementary grooves and projections, one of said members being of elastic material whereby said ornament member may be snapped into said frame with said complementary parts engaging to lock said ornament member in said frame, and means on said members for guiding the engaging movement of said parts, one of said members having a lug and the other of said members having a recess for receiving said lug.

4. In combination, an ornament holder member comprising a frame having an opening, and an ornament member adapted to seat in said opening, said members being made of metal, the edge parts of said frame opening and of the ornament member having complementary grooves and projections, one of said members being of elastic material whereby said ornament member may be snapped into said frame with said complementary parts engaging to lock said ornament member in said frame, one of said members having spaced lugs and the other of said members having spaced recesses for receiving said lugs.

5. In combination, an ornament holder member comprising a frame having an opening, and an ornament member adapted to seat in said opening, said members being made of metal, the edge parts of said frame opening and of the ornament member having complementary grooves and projections, one of said members being of elastic material whereby said ornament member may be snapped into said frame with said complementary parts engaging to lock said ornament member in said frame, and means on said members for guiding the engaging movement of said parts, one of said members having spaced lugs and the other of said members having spaced recesses for receiving said lugs.

6. In combination, an ornament holder member comprising a frame having an opening, and an ornament member adapted to seat in said opening, said members being made of metal, the edge parts of said frame opening and of the ornament member having complementary grooves and projections, one of said members being of elastic material whereby said ornament member may be snapped into said frame with said complementary parts engaging to lock said ornament member in said frame, said ornament member having spaced lugs and said holder member having spaced recesses for receiving said lugs.
